E. F. BROWN

MOUTH WASHBASIN ATTACHMENT

Filed Sept. 5, 1922

Patented May 29, 1923.

1,456,841

UNITED STATES PATENT OFFICE.

ERIC FORSS BROWN, OF BUXTON, IOWA.

MOUTH WASHBASIN ATTACHMENT.

Application filed September 5, 1922. Serial No. 586,035.

To all whom it may concern:

Be it known that I, ERIC F. BROWN, a citizen of the United States, and a resident of Buxton, in the county of Monroe and State of Iowa, have invented a certain new and useful Mouth Washbasin Attachment, of which the following is a specification.

The object of my invention is to provide a mouth wash basin attachment adapted to be used in connection with a lavatory, the parts being simple, durable, and comparatively inexpensive.

Still another object is to provide an attachment for lavatories wherein a funnel shaped basin is used so that anything discharged into the basin will pass into the outlet pipe of the lavatory without coming in contact with the sides of the lavatory.

Still another object is to provide spring clips on the attachment wherein the parts may be moved and held in inoperative position.

With these and other objects in view, my invention consists in the construction, arrangement and combination of the various parts of my device, whereby the objects contemplated are attained, as hereinafter more fully set forth, pointed out in my claim, and illustrated in the accompanying drawings, in which:

Figure 1 is a perspective view of a lavatory with my improved attachment shown thereon, the dotted lines showing the position of my attachment when not in use.

Figure 2 is a sectional view taken on line 2-2 of Figure 1.

Figure 3 is a detailed, sectional view taken on line 3-3 of Figure 2.

Figure 4 is a detailed, sectional view showing the pivotal connection of the funnel shaped basin member; and

Figure 5 is a detailed, sectional view taken on line 5-5 of Figure 4, showing how the pivotal movement of the funnel shaped member is limited in one direction.

In the accompanying drawings, I have used the reference numeral 10 to indicate generally a lavatory which is provided with a slab 11 and downwardly extending apron 12. In the lower portion of the lavatory 10 is the discharge pipe 13. Extending through the slab 11 are the faucets 14 and 15. The parts just described are of the ordinary construction.

My attachment consists of a yoke member A comprising a pair of similar members 16

which are adapted to extend around the faucet 14. The ends of the members 16 project out beyond the faucet and are held together by means of a bolt 17 having the 60 thumb nut 18 thereon.

The opposite ends of the members 16 are spaced apart and slightly bowed for receiving a hollow tube or arm 19. The arm or tube 19 is secured to the member 16 by means 65 of the bolt 20. Pivotal movement of the arm 19 on the bolt 20 is permitted.

Slidably received within the arm 19 is the rod 21. A set screw mounted within the arm 19 may be operated for engaging the 70 rod 21 for limiting its sliding movement and also for preventing rotation of the rod 21 within the arm 19. The outer free end of the rod 21 is bifurcated as at 23.

A funnel shaped basin 24 is pivotally 75 mounted on the rod 21 by the following described construction. On the funnel shaped basin 24, I mount the bracket 25 which is provided with an outwardly extending ear 26. The ear 26 is designed to be received in 80 the bifurcated portion 23 of the rod 21. A pin 27 is extended through the bifurcated portion 23 and the ear 26 for forming the pivotal connection between the basin 24 and the rod 21.

In order to limit the pivotal movement of the basin 24 in one direction, I provide a pair of shoulders 28 on the ear 26. The bifurcated portion of the rod 21 engages the shoulders 28 and limits the pivotal movement of the basin 24 in one direction.

From the construction of the part just described, it will be seen that the basin member 24 has its top opening positioned directly above the outlet of the lavatory. In 95 this connection it may be mentioned that in using any solution for a mouth wash or for the cleaning of teeth, the "spitting" may be done into the basin 24, thus avoiding the necessity of "spitting" into the lavatory 100 proper.

When it is not necessary to use the basin 24, it may be swung upon its pivot 27 until it rests upon the arm 19 and rod 21. The entire yoke member A may be swung on the 105 faucet 14 for moving the entire attachment where it will not interfere with the use of the lavatory.

If desired, the set screw may be loosened so the rod 21 may be slid into the arm 19 110 and also for permitting rotation of the rod 21 within the arm 19. The members 16 of

the yoke A are provided with spring clips 29 on the ends adjacent to the arm 19.

- If it is desired, the arm 19 may be swung on a horizontal axis (bolt 20) for bringing 5 the arm 19 to a vertical position. When the arm 19 is in vertical position, the basin 24 may also be swung upon its pivot so that the attachment will be so positioned that it will not interfere with the use of the lavatory. 10 The spring clips are sufficiently strong enough to hold the parts in either of their positions.

It will be seen that my attachment is very simple and adds materially to the sanitation 15 of the lavatory proper.

Some changes may be made in the construction and arrangement of the various parts of my invention, without departing 20 from the real spirit and purpose of my invention and it is my intention to cover by

my claim, any modified forms of structure or use of mechanical equivalents which may be reasonably included within its scope.

I claim as my invention:

In a device of the class described in combination with a lavatory having a faucet thereon, a funnel shaped basin arranged to be received in the lavatory, means for supporting said basin, said means including a yoke member mounted on the faucet, a telescoping arm pivotally secured to said yoke member at one end and to the basin at the other end so that the basin may be swung on a pivot to position where it will not be received within the lavatory, said yoke being provided with a pair of resilient clip members for retaining the arm in one of its positions.

Des Moines, Iowa, June 26, 1922.
ERIC FORSS BROWN.
